(57) **CLAIM**

The ornamental design of a sanitizing humidifier as shown and described.

DESCRIPTION

FIG. 1 is a front, top, left perspective view of a sanitizing humidifier, showing the new design according to a first embodiment;

FIG. 2 is a front, top, right perspective thereof;
FIG. 3 is a rear, top, right perspective view thereof;
FIG. 4 is a rear, top, left perspective view thereof;
FIG. 5 is a front, bottom, left perspective view thereof;
FIG. 6 is a front, bottom, right perspective view thereof;
FIG. 7 is a rear, bottom, right perspective view thereof;
FIG. 8 is a rear, bottom, left perspective view thereof;
FIG. 9 is a front view thereof;
FIG. 10 is a rear view thereof;
FIG. 11 is a right view thereof;
FIG. 12 is a left view thereof;
FIG. 13 is a top view thereof;
FIG. 14 is a bottom view thereof;
FIG. 15 is a front, top, left perspective view of a further example of a sanitizing humidifier, showing the new design according to a second embodiment;
FIG. 16 is a front, top, right perspective thereof;
FIG. 17 is a rear, top, right perspective view thereof;
FIG. 18 is a rear, top, left perspective view thereof;
FIG. 19 is a front, bottom, left perspective view thereof;
FIG. 20 is a front, bottom, right perspective view thereof;
FIG. 21 is a rear, bottom, right perspective view thereof;
FIG. 22 is a rear, bottom, left perspective view thereof;
FIG. 23 is a front view thereof;
FIG. 24 is a rear view thereof;
FIG. 25 is a right view thereof;
FIG. 26 is a left view thereof;
FIG. 27 is a top view thereof;
FIG. 28 is a bottom view thereof;
FIG. 29 is a front, top, left perspective view of another example of a sanitizing humidifier, showing the new design according to a third embodiment;
FIG. 30 is a front, top, right perspective thereof;
FIG. 31 is a rear, top, right perspective view thereof;
FIG. 32 is a rear, top, left perspective view thereof;
FIG. 33 is a front, bottom, left perspective view thereof;
FIG. 34 is a front, bottom, right perspective view thereof;
FIG. 35 is a rear, bottom, right perspective view thereof;
FIG. 36 is a rear, bottom, left perspective view thereof;
FIG. 37 is a front view thereof;
FIG. 38 is a rear view thereof;

(Continued)

FIG. 39 is a right view thereof;
 FIG. 40 is a left view thereof;
 FIG. 41 is a top view thereof; and,
 FIG. 42 is a bottom view thereof.
 The broken depict portions of the sanitizing humidifier that
 form no part of the claimed design.
